UNITED STATES PATENT OFFICE.

JOSEPH KOEHLER, OF NEW YORK, N. Y.

DESIGN FOR AN ENVELOPE.

SPECIFICATION forming part of Design No. 15,654, dated December 30, 1884.

Application filed October 4, 1884. Term of patent 3½ years.

To all whom it may concern:

Be it known that I, JOSEPH KOEHLER, of the city, county, and State of New York, have invented a new and original Design for an Envelope, of which the following is a full, clear, and exact description, reference being had to the accompanying drawings, making part of this specification, in which—

Figures 1 and 2 represent rear views of an envelope made according to my design, Fig. 1 showing the same open, and Fig. 2 closed.

Similar letters of reference indicate corresponding parts.

The design relates to an envelope for New Year's, wedding, and other cards; and it consists of a closing flap of nearly the same size as the body of the envelope, said closing flap having indented sides, rounded-off corners, and symmetrically-curved portions at the lower edge, which unite in a center point.

In the drawings, A represents the body of an envelope, and B the closing flap of the same. The flap B is made of nearly the same

size as the body A of the envelope, and having indented sides b b, rounded-off corners d d, and slightly-curved portions e e at the lower edge of the flap, which curved portions meet in a center point, f. A flap of this shape covers nearly the entire body of the envelope A, and imparts a neat and ornamental appearance to the same.

Having thus described my design, I claim as new and desire to secure by Letters Patent—

The design for an envelope, consisting of a body, A, and a closing flap, B, the latter having indented sides b b, rounded-off corners d d, and slightly-curved portions e e meeting at a center point, f, of the lower edge of the flap, as shown and described.

In testimony that I claim the foregoing as my invention I have signed it this 22d day of September, 1884.

JOSEPH KOEHLER.
